UNITED STATES PATENT OFFICE

156,086

DESIGN FOR A CIGARETTE LIGHTER

Irving Florman, New York, N. Y.

Application July 28, 1949, Serial No. 4,179

Term of patent 14 years

(Cl. D48—27)

To all whom it may concern:

Be it known that I, Irving Florman, a citizen of the United States, residing at New York, in the county of New York and State of New York, have invented a new, original, and ornamental Design for a Cigarette Lighter, of which the following is a specification, reference being made to the accompanying drawing, forming a part thereof.

Fig. 1 shows in side elevation a cigarette lighter, showing my new design;

Fig. 2 is a view from the left-hand side of Fig. 1;

Fig. 3 is a view from the right-hand side of Fig. 1;

Fig. 4 is a top plan view thereof; and

Fig. 5 is a bottom plan view thereof.

The opposite side of the lighter corresponds in appearance to the side shown in Fig. 1.

I claim:

The ornamental design for a cigarette lighter substantially as shown and described.

IRVING FLORMAN.
